UNITED STATES PATENT OFFICE.

JOHN W. HARTMANN, OF BROOKLYN, NEW YORK.

SIFTING GRATE.

Application filed October 14, 1920. Serial No. 416,925.

To all whom it may concern:

Be it known that I, JOHN W. HARTMANN, a citizen of the United States, residing at Brooklyn, in the county of Kings and State 5 of New York, have invented certain new and useful Improvements in Sifting Grates, of which the following is a specification.

The invention relates to grates for furnaces and other combustion apparatus from 10 which it is necessary to remove accumulations of residual substances, such as ashes and clinkers, and the object thereof is to provide means whereby these residues may be readily separated from the igneous fuel 15 without extinguishing the fire or materially retarding combustion.

The combustion in furnaces of all types is generally very intense when the fire is new, but as the combustion proceeds the 20 residual incombustible earths and stones, which are associated with the fuel, gradually increase in quantity and retard combustion until the attendant, with more or less difficulty, removes them from the combustion 25 zone. This result is usually attained by shaking the grate to thereby cause the ashes to pass between the grate bars and into the ash pit of the furnace, but this shaking operation does not remove such masses of 30 clinkers as are too large to pass between the grate bars, and these masses often become so great as to necessitate the dumping of the fire, and the kindling of a fresh one. The intensity of the combustion is largely dependent upon the strength of the draft, and this is strongest when the fuel is first laid, since at that time the fuel has not been compacted, and the interstices have not become 35 filled with the incombustible residues which 40 later obstruct the draft and lessen the supply of air until the fire dies down and no longer supplies an adequate quantity of heat.

The grate which I have devised overcomes 45 the aforesaid difficulties, provision being therein made not only for the removal of ashes and the simultaneous loosening of the fuel mass, but for rendering the clinkers accessible through the feed door of the furnace. These and other advantages to be derived from the use of my grate, will be understood by those who read the following

description in connection with the accompanying drawings in which—

Figure 1 is a view of a furnace shown in 55 front elevation parts being broken away;

Figure 2 is a view of the grate looking toward the front end thereof;

Figure 3 is a vertical longitudinal view 60 of the furnace, parts being broken away;

Figure 4 is a sectional view of part of the sifter showing one of the agitating pins in elevation, and

Figure 5 is a fragmentary sectional view 65 showing the sliding connection between the grate and the sifter.

The furnace 1 may be of any usual type, and said furnace is provided with a fire box 2 within which is disposed the grate 3.

This grate, which is preferably semi-cylindrical in form, contains transversely arranged grate bars 4 separated by washers 5 of any desired thickness as may be determined by the fineness of the fuel, and these bars are united by tie rods 6 extending 70 through aligned perforations of said bars in a usual manner. The grate is supported by two trunnions 7, 8, respectively mounted in bearings 9, 10, arranged at the front and the back of the furnace, the trunnion 7 being 75 long enough to protrude through the front wall of the fire box where it is squared to receive a suitable actuating handle.

The front plate 11 of the grate, is provided with spaced bars 12, and the back plate 13 of said grate, is likewise provided with spaced bars 14, the tie rods 6 being 80 extended through both of these plates in order to hold them securely in their respective positions on the grate.

The grate is provided, at each of its upper edges, with a longitudinal side bar 15 having an undercut groove 16, and these bars are secured to the grate by screws 17.

Associated with the grate is a removable 95 sifter 18 which, like the grate, is preferably of semi-cylindrical shape, whereby the grate and the sifter constitute a complete cylinder within which the charge of fuel may travel circumferentially as the grate is revolved or 100 oscillated on its trunnions to thereby agitate said charge and relieve it of its ash content. During this operation the fuel charge will, by gravitational action, continuously

tumble down the rising wall of the device, thereby loosening the fuel to such extent as admit of a free flow of air therethrough when the ash-sifting operation is completed 5 and the furnace resumes its normal operation. The clinkers which appear at the surface of the mass of agitated fuel, may, if too large to eventually be sifted out with the ashes, be conveniently removed through the 10 feeding orifice of the furnace which, as shown, extends above the top of the grate a sufficient distance to admit of the insertion and withdrawal of the sifter which is adapted to be interlocked with the grate in a 15 movable manner. The sifter is open at the ends, and affords, therefore, no obstruction to the insertion of an instrument through the feeding orifice of the furnace by means of which the clinkers may be taken out.

20 The sifter includes front and rear bowed angle irons 19 each having at each of its ends a foot 20 resting on and secured to a slide bar 21 that is provided with a male dovetail 22 loosely fitting the under-cut 25 groove of the corresponding side bar 15 to insure the easy withdrawal of the sifter after it has subserved its function, the foot and the slide bar being firmly united by machine screws 23. The sifter also includes a 30 frame-work 24 of flat iron, suitably secured to the slide bars 21, and a longitudinal rib 25, which is fastened to the angle irons 19 and the frame-work 24 by rivets or other suitable devices.

35 Extending through holes in the rib 25, are depending and preferably pointed pins 26 arranged in a row, and each of these pins is provided with a shoulder 27. A wire-mesh screen is sustained by the frame work 40 24, the lower edges of said screen being retained by hook bolts 29 suitably anchored in the angle irons or the frame-work of the sifter. The arched portion of the screen is held in position by the pins 26 which extend 45 through said screen at several points.

The doors of the furnace are oppositely hinged, and are of such shape as to cover the feeding orifice of the furnace, which is of circular form to admit of access to both 50 the sifter and the grate, and each door is cut away, as shown, to permit of the protrusion of the trunnion 7.

The operation of a furnace embodying my 55 invention is easily understood and conducted. The fire is started in the usual way, and combustion of the fuel is allowed to proceed uninterruptedly until it is necessary to eliminate the accumulations of incombustible matter and add new fuel. When this necessity arises, the front doors of the furnace 60 will be opened, and the sifter will be inserted over the grate, the male dovetail being engaged with the under-cut groove at the top of the sifter to thereby cause said 65 sifter to become, in effect, a part of the grate

and to partake of all of the movements thereof. As soon as the union of these elements is thus established, the grate will be revolved or oscillated on its trunnions until the unconsumed fuel is freed of its ashes 70 and small clinkers and both have escaped through the spaces between the grate bars or through the meshes of the screen of the sifter, and fallen into the ash-pit of the furnace. It will be found that a portion, at 75 least, of the clinkers which are at first too large to pass between the grate bars or through the meshes of the screen, will be broken up by the pins of the sifter into pieces small enough to be sifted out with the 80 ashes, and that, in consequence of this subdivision of such clinkers as may be disintegrated, only a few clinkers will have to be removed through the furnace door. The pins, furthermore, greatly assist in the separation 85 of the ashes and the fuel, since they are set close enough to themselves act as sifters, and they also hold and carry with them a considerable quantity of the fuel, thereby reducing the quantity of unburned 90 lumps thereof which otherwise would be present on parts of the sifter screen and interfere with the escape of the ashes.

The grate and the sifter are both capable of eliminating the ashes of the charge of 95 fuel, but ordinarily the sifter will be utilized because it is especially adapted for the work.

When the fire has been cleaned in the manner above described, the grate will be returned to its normal pendent position, and 100 the sifter removed through the front opening of the furnace. Fresh fuel may then be supplied, and combustion allowed to proceed.

Having thus described my invention, what 105 I claim is:

1. A grate comprising segmental end portions and intervening fuel-sustaining bars, combined with a removable arcuate and open-ended ash sifter arranged to receive 110 materials from said fuel-sustaining bars when said grate is inverted.

2. The combination with a furnace having a revoluble grate, of a longitudinally-removable sifter for said grate, the end of 115 the combustion chamber being provided with an opening to permit the sifter to be attached to the grate and removed at will.

3. The combination with a combustion chamber having an opening in an end wall 120 thereof, of a revoluble arcuate grate substantially aligned with said opening, and an ash sifter for said grate adapted to be longitudinally removed from said grate through said end opening.

4. The combination with a combustion chamber having an end opening of a grate revolvably mounted in said combustion chamber, and a sifter removable through said opening and interlocked with said grate. 130

5. The combination with a combustion chamber having an end opening, of bearings for the trunnions of a revoluble grate, a revoluble grate mounted in said bearings, a sifter detachably connected with said grate, and a closure for said end opening, said end opening being of such area as to expose said grate and said sifter when said closure is removed from said opening.
- 10 6. The combination with a grate, of a sifter having a sliding and interlocking engagement with said grate.
7. The combination with a rotary grate, of a detachable sifter having a row of spaced pins extending parallel with the axis 15 on which said grate rotates.
8. The combination with an arcuate revoluble grate having longitudinal grooves in its edges, of a removable ash sifter provided with slide bars at its sides conforming to 20 and interlocking with said grooves.

In testimony whereof I affix my signature.

JOHN W. HARTMANN.
